UNITED STATES PATENT OFFICE

2,474,623

DEVICE FOR SHARPENING CUTLERY

William C. Flanning, Cedar Rapids, Iowa

Application February 7, 1948, Serial No. 6,914

5 Claims. (Cl. 51—187)

1

This invention relates to cutlery sharpening devices, and particularly to a device of that nature which employs a sharpening element in the form of an abrasive coated tape.

A primary object of my invention is the provision of an improved device for sharpening cutlery and one employing a replaceable abrasive tape.

Another object of my invention is the provision, in such a device, of improved means for mounting and tightening the abrasive tape.

A further object of my invention is the provision of a relatively simple device of this nature which may be produced at low cost.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view in perspective of a cutlery sharpening device constructed in accordance with a preferred embodiment of my invention.

Figure 2 is a view in top elevation of the sharpening device shown in Figure 1.

Figure 3 is a view in longitudinal section taken along the line 3—3 of Figure 2.

Figure 4 is a view in transverse section taken along the line 4—4 of Figure 3, and

Figure 5 is a fragmentary view in longitudinal section similar to Figure 3, but shows the device as it appears when partially opened.

Referring now to the drawings, in which a box-like base member, indicated generally at 11, has hingedly secured, at one end thereof, a top member indicated at 12. The base member is preferably formed from sheet metal with a bottom wall 13, upwardly extending side walls 14 and an end wall 15 at one end thereof. The end wall is preferably welded or otherwise permanently secured, along its vertical edges, to the adjacent ends of the side wall portions 14. The portions of these side walls, opposite the end wall 15, are cut in the shape shown to provide spaced ears 16 and 17. These ears are apertured, as at 18, to receive a bolt 19, this bolt being secured in position by the wing nut 21.

A portion of the bottom wall 13, generally between the ears 16 and 17, is bent upwardly at right angles to the bottom, as shown at 22, for purposes which will hereinafter become more ap-

2

parent. The side wall portions 14 of the base are provided with a pair of aligned, vertically elongated holes 23 and 24, and these openings are positioned to receive an abrasive tape tightening device preferably in the form of a roller 25. This roller has end portions 26 and 27 of reduced diameter adapted to be received in the elongated holes and to be both rotatable and vertically slideable therein.

10 The top member 12 is of somewhat similar shape to the base member 11, and includes a top wall portion 28 having depending side walls 29—30 and an end wall 31. The vertical edges of these side and end walls are welded or otherwise secured together, as at 32, the opposite end portions of the side walls forming ear-like projections 33 having apertures therein for mounting on the hinge bolt 19. The top member is of such width as to hinge freely on the hinge pin 19 between the side walls of the base member and is of such length as to frictionally engage and bind a portion 34a of an abrasive coated tape 34 between the end walls 15 and 31 of the base and top members respectively.

25 This abrasive strip or tape is preferably in roll form with the roll 34c mounted on the hinge pin 19. A portion 34b of this abrasive tape, comprising the actual cutting or sharpening surface, overlies the top wall 28 of the upper member.

30 A portion 28a of the top wall is bent downwardly between the side wall portions 29 and 30 to form an upper binding member, and this member, extending entirely between the side walls 29 and 30, is so positioned as to frictionally engage the top curved end of the lower binder member 22 when the top and bottom members are closed or together as in Figures 1 and 3.

35 It should be noted that the lower binding member 22 does not extend entirely between the side walls 14—14 but instead is spaced away from each wall, as best shown in Figure 4, to permit the side walls 29 and 30 of the top member to pass downwardly therebetween. These side walls of the upper hinged member are notched out, as shown at 35, to engage the upper side of the abrasive tape tightener.

40 Installation of an abrasive tape in my improved sharpening device is as follows. The tape 34 is unwound from the roll 34c as needed, and with base and top opened as in Figure 5, is passed upwardly between the binding members 28a and 22 of the top and base members respectively. The strip is then passed downwardly beneath the tightener 25 and up through a slot 36 in the top wall 28 of the upper member. From this point

the strip extends over the upper surface 28, passes inwardly through a slot 37 in the end wall 31, and extends downwardly beneath the lower edge of the end portion 31.

Tension is maintained on the free end of the abrasive tape as the top member 12 is pressed down within the base and, at the same time, the tape tightening roller 25 is supported in the upper ends of the slotted openings 23 and 24 until such time as the roller is engaged by the side walls 29 and 30 within the notches 35-35. The slots 23 and 24 are of such length and are so positioned that the roller is engaged within the notches 35-35 at approximately the same time that the end wall member 31 starts to enter the base at which time the loose end of the tape will become securely bound therebetween.

The abrasive tape is also bound or clamped at the opposite end of the sharpening device where it passes between the upper and lower binding members 22 and 28a, these members being shaped and positioned to firmly grip the tape, as shown at 38, at approximately the same time the free end of the tape is secured. It may now be understood that, as the top member 12 is forced downwardly between the walls of the base 11, the roller 25 is also forced downwardly in its guide slots and thus serves to remove all slack from the portion 34b of the abrasive tape and holds it taut during use.

The base is provided with holes, as at 39, through which wood screws may be mounted to secure the entire unit to the surface of a work table or the like.

I have provided a tool which is well adapted for use in sharpening and maintaining a keen cutting edge on most types of cutlery and particularly butcher knives and other tools of similar nature.

A sharpening device such as I have herein described is adapted to be manufactured at relatively low cost. The abrasive surface is readily renewed and the device is particularly effective in tightening the abrasive tape, thus prolonging its useful life.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a cutlery sharpening device, a base member, a top member hingedly attached thereto adjacent one end thereof, an abrasive tape tightener comprising a member rotatably mounted in the base member, positioned transversely thereof and engageable by the top member to be forced downwardly thereby, an abrasive tape having a portion thereof looped downwardly beneath the tightener, extending lengthwise over the upper surface of the top member and having portions thereof frictionally engaged between adjacent end

55

60

65

portions of the top and base members adjacent opposite ends thereof.

2. In a cutlery sharpening device, a base member, a top member engageable therewith, an abrasive tape tightener comprising a member rotatably mounted in the base member, positioned transversely thereof and engageable by the top member to be forced downwardly thereby when the top member is engaged with the base member, an abrasive tape having a portion thereof looped downwardly beneath the tightener, extending lengthwise over the upper surface of the top member and having portions thereof frictionally engaged between adjacent end portions of the top and base members adjacent opposite ends thereof.

3. In a cutlery sharpening device, a base member, a top member engageable therewith, an abrasive tape tightener disposed between the top and base members and transverse thereto, an abrasive tape having a portion thereof looped downwardly beneath the tightener, extending lengthwise over the upper surface of the top member and having portions thereof frictionally engaged between adjacent end portions of the top and base members adjacent opposite ends thereof.

4. In a device for sharpening cutlery, a base member, a top member engageable therewith, an abrasive tape having a portion thereof overlying the top surface of the top member, means engaging and gripping said tape at points adjacent opposite ends of the said top surface of the top member, and a tightener comprising a transversely disposed member spaced from the top surface of the top member engaged with a portion of the abrasive tape between said engaging means, said tightener being operable by relative movement of top and base members.

5. In a device for sharpening cutlery, a base member, including upstanding side walls, a top member hingedly mounted on said base member, a tightener vertically movable relative to said base member and disposed between the side walls thereof, the top member having depending side walls engageable with said tightener, an abrasive tape overlying said top member and having a portion thereof engaged by said tightener, and means for gripping said tape on opposite sides of the portion thereof engaged by the tightener, said gripping means and said tightener being operable by hinging movement of the top member toward the base member.
